UNITED STATES PATENT OFFICE.

EARL C. RODMAN, DECEASED, LATE OF TUSCOLA, ILLINOIS; BY BLANCHE RODMAN,
ADMINISTRATRIX, OF TUSCOLA, ILLINOIS.

ADAPTER COIL.

Application filed October 9, 1925. Serial No. 61,570.

This invention relates to coils, and more particularly to a coil especially adapted for use in telephony.

One of the main objects of the invention is to provide a coil so constructed as to be readily connected to a switch board of the magneto type, this coil when properly connected rendering it possible to convert the magneto type of switch board and exchange into common battery service without necessitating any material changes in the switch board or exchange. A further object is to provide a coil of this character of comparatively simple and inexpensive construction, the various elements of which are so arranged and related as to enable the coil to be readily connected to a source of electrical energy, such as a storage battery, a telephone instrument and the switch board in such manner that energy from the battery can be utilized for energizing the telephone instrument and also for energizing the switch board apparatus.

Further objects will appear from the detailed description.

In the drawings:

Fig. 1 is a diagram showing the coil as applied to a switch board of known type.

Fig. 2 is a section through the coil casting, the coil being shown in elevation.

Fig. 3 is a diagram of the connections of the windings of the coil.

Fig. 4 is an enlarged detail of the overlapping outer end portions of some of the laminations of the core.

Fig. 5 is a fragmentary sectional view through the head and the upper portion of the coil casing.

The coil is constructed in two sections each section being wound on a fiber spool 1. Each section of the coil is formed of two windings, these windings being wound simultaneously and similarly. In the coil illustrated, which is intended for use in connection with a 24 volt storage battery, the windings are formed of 1500 turns each of 29 gauge (B. & S.) enamelled copper wire, each winding of each section being formed of 750 turns. The windings are all wound similarly. The spools 1 are mounted upon a core 2 formed of strips of soft iron, this core being

of laminated construction. One half of the strips of the core are bent about the outer portions of the spools with their ends overlapping, the ends of the outermost strips being secured together in any suitable manner so as to confine the other strips in position. The other half of the strips are similarly bent in the opposite direction. This provides, in effect, a shell type of core of laminated construction which extends through and encloses the windings of the sections of the coil so as to effectually conserve the energy induced in the coil and obtain a close magnetic coupling between the windings of the coil.

Referring to the diagram (Figure 3) one winding of the coil is formed in two sections 3 and 3^a, the outside end of section 3 being connected directly to the inside end 70 of section 3^a so that these two sections, in effect, form a single winding. The outer end 4 of section 3 and the outer end 4^a of section 3^a are intended to be connected to a switch board in a manner to be described. The other winding of the coil is formed of two sections 5 and 6 which are electrically insulated from each other. The outside end 6^a of section 6 and the outer end 5^a of section 5 are intended to be connected to an electric battery in a manner to be described. The inner end 5^b of section 5, which is really the outside end of this section, and the outer end 6^b of section 6, which is really the inside end of this section, are connected to the line leading from the switch board to a telephone instrument which is to be energized from the battery and connected to the switch board.

In practice, after the coil has been properly assembled, it is placed in a suitable casting 7 in the upper end of which is secured a wooden closure member or head 8. Six soldering lugs 9 are secured in the head 8 and are connected to the respective terminals of the coil sections. Two of these lugs adjacent which are the letters SW.B. are connected to the terminals 4 and 4^a. The lugs marked L are connected to the two terminals 5^b and 6^b. The remaining two lugs are connected to the opposite sides of the battery. In Figure 3 I have shown terminal 6^a connected

to the negative side of battery B and terminal 5^a connected to the positive side of the battery, though these connections can be reversed without affecting the operation of 5 the coil.

In Figure 1 I have indicated the manner of using the coil in connection with a switch board SW.B. of the magneto type which includes a jack J and a drop D of known 10 type connected in a known manner to wires 10, these wires being connected to the soldering lugs SW.B. The soldering lugs L are connected by wires 11 to a telephone instrument T in a known manner, 15 this instrument being of known type such as is commonly used in connection with common battery or central energy exchanges. The poles of battery B are connected to the two remaining lugs, as illustrated, and the 20 positive pole of the battery is preferably grounded at 12. This grounding of the battery is not necessary but is preferred as serving to drain off static charges and also as preventing, to a considerable extent, cross 25 talk between the wires. While I have illustrated but a single coil in connection with the switch board, there can be mounted any number of coils on a rack either on or adjacent 30 the switch board, these coils being connected in the manner described to the individual lines, thus providing simple and efficient means whereby a magneto exchange can be readily converted to a central energy or common battery.

35 With the connections illustrated in Figure 3, when the receiver is lifted from the hook of the telephone instrument T, the circuit of battery B is closed and there is an instantaneous rush of current through sections 5 and 6 of the right hand winding of the coil as considered in Figure 3, these 40 sections being connected in series with the battery and with the telephone instrument. This rush of current induces a current in 45 sections 3 and 3^a of the left hand winding of the coil, this induced current flowing through the wires 10 and energizing the coil of the annunciator or drop of the switch board thus releasing the shutter which drops 50 and calls the operator's attention to the fact that this circuit has been closed. To connect the calling party of the instrument T with the called party, the operator inserts 55 a jack plug into the jack J thus breaking the annunciator circuit and connecting the wires 10 to the instrument of the party called. During use of the telephone T the vibrations of the diaphragm of the transmitter of the instrument will generate a 60 fluctuating current in sections 5 and 6 of the right hand winding of the coil, as considered in Figure 3. This will induce a similar fluctuating current in the sections 3 and 3^a of the right hand winding, which 65 sections are connected in series with the wires

10 and, by means of the jack plug, to the instrument of the party called. In this manner, the battery B produces energy which is utilized directly to energize the transmitter of the instrument T and also, by induction, 70 produces the energy which is utilized for transmitting the message over the wires 10. In the event that the party at the telephone T is called, the operator by inserting the jack plug into the jack J connects the wires 75 10 in series with the calling party and the fluctuating or alternating current which is caused to flow through sections 3 and 3^a of the coil winding by operation of the buzzer or other signalling device at the switch board, will induce a similar current in sections 5 and 6 of the other winding thus 80 operating the buzzer or bell of the telephone instrument T. When the receiver of this instrument is lifted from its hook the circuit is closed and conversation between the parties may be carried on as before.

The telephone instrument T as well as the jack J and the drop D are all standard equipment and well known in this art and need not be further illustrated or described in detail.

What I claim is:

1. In the combination with a jack and drop of a telephone switchboard, a coil having two windings, the primary winding of said coil being continuous and connecting with said jack and drop, the secondary of said coil divided into two sections, an outer end of one of said sections communicating with a telephone instrument, the inner end of the same section communicating with a source of electrical energy, the corresponding end of the opposite section connecting with the other pole of source of said electrical energy and the outer end of the opposite section communicating with the aforesaid telephone instrument.
2. In combination with a jack and drop switchboard of a telephone instrument, a source of electrical energy, a coil of two lateral simultaneous windings, the primary of said coil being continuous and communicating with the said jack and drop, and the secondary of said coil being divided into two sections, the outer end of one of said sections and the inner end of the opposite section communicating with the said telephone instrument, and the outer end of the last named section and inner end of the opposite section to it connecting with the said source of electrical energy, said coil being wound around a core of laminated overlapping metallic strips.
3. In combination with a jack and drop switchboard, a telephone instrument, a source of electrical energy, and a coil of two lateral simultaneous windings, the primary of said coil being continuous and communicating with said jack and drop, the secondary of

said coil being divided into two sections, connection between the outer end of one section and the inner end of the opposite section with the said telephone instrument, a 5 connection between the outer end of the last mentioned section and the inner end of the opposite section to it with a source of electrical energy, said coil containing a laminated metal core and being mounted in a casing with the described terminals or end protrud- 10 ing therefrom.

In testimony whereof I affix my signature.
BLANCHE RODMAN,
Administratrix of Earl C. Rodman, deceased.
